UNITED STATES PATENT OFFICE.

ALBERT R. WOLF, OF SNYDER, NEBRASKA.

FASTENER FOR CONTAINERS.

Application filed October 9, 1925. Serial No. 61,527.

To all whom it may concern:

Be it known that I, ALBERT R. WOLF, a citizen of the United States, residing at Snyder, in the county of Dodge and State of Nebraska, have invented certain new and useful Improvements in Fasteners for Containers, of which the following is a specification.

The present invention relates to fasteners for closures of shipping crates, boxes, or any other suitable containers, and more particularly to a fastener for a slideable closure. The principal object of the invention is to provide a highly novel fastening means for the slideable closure which is simple in its construction, efficient and reliable in its operation, strong, durable, easy to manipulate, not likely to easily become out of order, compact and convenient, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:—

Figure 1 is an elevation of the box or container embodying the features of my invention.

Figure 2 is a fragmentary enlarged elevation thereof looking to the right of Figure 1 and showing the fastener in detail, and

Figure 3 is a detail section through the fastener.

Referring to the drawing in detail it will be seen that 5 designates any sort of container which is provided on one side with a longitudinally or transversely extending cleat 6 adjacent the upper edge and on its opposite side with a similarly extending cleat 7 spaced from the upper edge. A bar 8 is attached to one edge of the cover 9, depends therefrom, and terminates at its bottom end in a rectangularly disposed extension 9 fitting under the cleat 6. A bar 11 is mounted at the opposite edge of the cover 9 and slides on top of the cleat 7. An angle plate 12 is fixed to the cover 9 and to the bar 11. A pair of links 13 and 14 are pivoted at spaced points to the plate 12, and converge downwardly toward each other. A clamping device indicated generally by the letter A is pivotally engaged with the

lower ends of the links 13 and 14. This clamping device A includes a casing 16 having slidably mounted therein the shank 17 of a shoe 18 adapted to bear against the under surface of the cleat 7. This shank 17 is provided with an oval shape opening 20 in which is movable the cam 19 on the shaft 21 journaled through the casing and operable by the crank 22. When the crank 22 is in the position shown in the drawings, the shoe 18 is held in frictional engagement with the under surface of the cleat 7, thereby preventing sliding of the cover 9. Thus the cover 9 may be held in a fully closed position against accidental displacement and may be similarly held in a partially open position. To slide the cover it is only necessary to swing the crank 22 in the position indicated by the arrow in Figure 3.

It is thought that the construction, operation, and advantages of this invention will now be clearly understood without a more detailed description thereof. The present embodiment of the invention has been disclosed in detail merely by way of example since in actual practice it attains the features of advantage enumerated as desirable in the statement of the invention and the above description. It will be apparent that changes in the details of construction and in the combination and arrangement of parts may be resorted to without departing from the spirit or scope of the invention as herein-after claimed or sacrificing any of its advantages.

Having thus described the invention, what I claim as new is:—

1. In combination, a container, a cover slidably mounted on the container, a cleat on the container, a pair of links engaged with the cover, a casing supported by the links, a shoe, a shank extending from the shoe into the casing, a cam in the casing for pushing the shank therefrom and forcing the shoe into frictional engagement with the cleat, and means for operating the cam.

2. A fastening device for a container; wherein the container includes a slideable cover; comprising a cleat adapted to be mounted on the container, a pair of links adapted to be engaged with the slideable cover, and a clamp supported by said links and adapted to engage under said cleat to frictionally engage the same to prevent the sliding of the slideable cover.

3. In combination, a container, a cleat on

one side of the container, a slidable cover on the container, a bar fixed to the cover and 5
slidable on the top of the cleat, an angle plate attached to the edge of the cover adjacent the bar, a pair of links attached to the angle plate, and depending downwardly therefrom and converging toward their bottom ends, a clamping mechanism engaged with one link and adjustably engaged with 10
the other link.

4. In combination, a container, a cleat on one side of the container, a slidable cover on the container, a bar fixed to the cover and 15
slidable on the top of the cleat, an angle plate attached to the edge of the cover adj-

cent the bar, a pair of links attached to the angle plate, and depending downwardly therefrom and converging toward their bottom ends, a clamping mechanism engaged with one link and adjustably engaged with 20
the other link, said clamping mechanism including a casing, a cam rotatable in the casing, means for rotating the cam, a shank 25
slidable in the casing and having an oval shaped opening for receiving the cam, and a shoe on the shank adapted to engage the under surface of the cleat.

In testimony whereof I affix my signature.

ALBERT R. WOLF.
